POWER BRAKE TEST STAND

Maurice L. Schwarz, Middletown, Conn., assignor to The Eis Automotive Corporation, Middletown, Conn., a corporation of Connecticut

Filed Oct. 19, 1960, Ser. No. 62,538

Term of patent 14 years

(Cl. D52—6)

FIG. 2

FIG. 1 is a perspective view, looking toward the front and right-hand side, of a power brake test stand showing my new design; and

FIG. 2 is an elevational view of the left-hand side thereof.

I claim:

The ornamental design for a power brake test stand, as shown.
